UNITED STATES PATENT OFFICE.

FRANKLIN S. SMITH, OF PHILADELPHIA, PENNSYLVANIA.

APPARATUS FOR DESTROYING INSECTS BY MEANS OF ELECTRICITY.

1,016,450.

Specification of Letters Patent.

Patented Feb. 6, 1912.

Application filed January 7, 1911. Serial No. 601,284.

To all whom it may concern:

Be it known that I, FRANKLIN S. SMITH, a citizen of the United States, residing in the city and county of Philadelphia, State of Pennsylvania, have invented certain new and useful Apparatus for Destroying Insects by Means of Electricity, of which the following is a specification.

My invention relates to apparatus or means for destroying insects, their eggs, larvae and pupae, by means of electricity.

The apparatus includes means for the production of an electric discharge to the action of which the said insects, etc., are subjected. The insects, their eggs, larvae or pupae, which it is particularly desired to destroy, are those which are destructive in various ways and which destroy articles of various kinds and cause great loss of and injury to property.

In the apparatus illustrated herein, the discharges are caused by means of an alternating current of commercial or slightly higher high frequency but it should be understood that a uni-directional current may be employed.

Without attempting to enumerate all of the various articles and objects which may be treated for the purpose of destroying the destructive insects which infest and may destroy them, I may mention food products, such as cereals, prepared breakfast foods of the various kinds, dried fruits, flour, figs, etc.; tobacco, either in the leaf state or after it has been converted into some form of manufactured product, such as cigars and cigarettes; wearing apparel, such as furs, woolens, etc.; and books, papers, etc. As is well known, all of these various articles may be infested and are frequently not only injured but are actually destroyed by the insects which are peculiar thereto.

There is a species of worm, more apt to be found in the warmer countries, commonly called the book worm, which attacks books, papers, etc., and causes great injury and damage thereto.

Employment of my invention is not limited to the objects and articles designated above but it may be employed for the treat-

ment of many others not named for the destruction of such insects as may infest them and cause their deterioration and destruction.

In order that the apparatus embodying my invention, whatever its form of construction, may accomplish the best results, it is necessary generally that the objects and articles treated shall be free from metallic substances, though there are some cases which form an exception to this rule.

The objects and articles to be treated are placed within and subjected to the action of electrical discharges and if there should be present any metallic substances they would act as isolated capacities and would cause a condensation of the electrical current which passes through the objects or articles and thus prevent contact of the current with certain portions of the object or article being treated, with the result that the material located in proximity to such metallic substances would be unaffected and unacted upon by the discharge current through the articles or object being treated.

Cereals and breakfast foods generally may be treated in bulk or in the usual card board boxes in which they are sold but when treated in such boxes care must be taken to prevent the presence of metal upon the said boxes. Also cigars and cigarettes may be treated in bulk or in the boxes in which they are sold or marketed. The difficulty, however, in treating cigars and cigarettes in boxes as suggested is that such boxes usually are provided with decoration which includes a greater or less amount of metallic substance which would interfere with the successful operation of my invention and discovery in the treatment of cigars in boxes; hence, cigars and cigarettes preferably should be treated in bulk and before being placed in the boxes in which they are marketed. In the treatment of clothing, care must be exercised to prevent the presence of metallic buttons because if such buttons are present they act as conductors, as already indicated, and cause a concentration of the current at the points where they are located so as to prevent the action of the current upon the

portions of the material of the garment which are in proximity to and surround the said buttons.

In the employment of apparatus embodying my invention in the treatment of articles, such as are above suggested, care must be exercised to prevent their oxidation and carbonization by the use of discharge sparks which are of too great capacity. The capacity of the sparks may be controlled in various ways and by experience it has been found that sparks may be produced and employed in the carrying out and practicing of my invention which are of sufficient capacity to destroy the insects, their eggs, larvæ or pupæ, which may be upon the articles treated but which will not cause injury to the articles themselves.

In the large number of experiments which 20 I have heretofore carried out in the development of my invention, I have discovered that when carefully and intelligently employed and operated, my invention will destroy all of the insects in whatever stage of 25 their development, whether as eggs, larvæ, pupæ or adults, which may infest or be present in or upon the articles or objects treated.

In the accompanying drawings I have 30 illustrated a convenient embodiment of my invention but it will be understood and will be apparent from the description of the same which follows, that my invention may be embodied in other forms of construction.

In the drawings:—Figure 1 is a top plan 35 view of an apparatus embodying my invention; Fig. 2 is a sectional side elevation of the same; and Fig. 3 is an enlarged view on the line 3—3 of Fig. 1 showing more clearly a detail of construction.

40 Referring to the drawings:—the numeral 1 designates a source of alternating electric current, 2 a switch, and 3 a variable or adjustable resistance which is connected in series with the primary coils of a number of 45 step-up transformers 5 which are connected in multiple with the source 1 of current. The opposite ends of the secondary coils of the said transformers 5 are connected with the oppositely disposed electrodes 6 and 7. 50 These electrodes are arranged in two rows, as is indicated in Fig. 1 of the drawings. The electrodes in the two upper rows are arranged in staggered relation with respect to each other, as is clearly shown in Fig. 1, 55 while those in the two lower rows are arranged in staggered relation with respect to each other in the same manner. The number of transformers, electrodes, and arrangement of the latter may be varied as desired.

60 Preferably, though in some cases it may be found to be unnecessary, the electrodes should respectively terminate in a single point in order that all portions of the object or article being treated, whether in boxes or

otherwise, may be subjected to the action of 65 the discharge. It has been found that if electrodes of considerable length and respectively provided with a plurality of points are employed and articles are treated in boxes, it happens that the discharge takes 70 place between points of opposing electrodes which are nearest to alinement with a side of the said boxes along the said side so that the material in the boxes may not be acted upon. In such cases, the insects or their 75 eggs, larvæ or pupæ, which may be present in the articles and which it is desired to destroy, remain unharmed.

The electrodes 6 and 7 are supported in depressions or seats 10 and 11 formed in 80 plates 12 and 13 of non-conducting or insulating material, such as glass or porcelain. It will be understood that when the switch 2 is closed an electric discharge takes place 85 between electrodes 6 and 7, such discharge consisting of well defined sparks and also of what is known as effluvæ, both of which are visibly apparent. The plates 12 and 13 are supported in any suitable manner, as for instance upon posts or standards 14 and 15. 90 It will be observed that the electrodes 6 project a short distance below the lower side of the surface of the plate 10 while the ends of the electrodes 7 are located a short distance below the upper side of the plate 11. 95

20 designates a conveyer of suitable insulating or non-conducting material supported upon revoluble wheels 21 driven from any suitable source of power (not shown), by means of which articles being 100 treated are conveyed into and across the space between the electrodes 6 and 7. The electrodes in the respective rows should be arranged close together and those in the respective plates upon which they are supported should be in staggered relation with respect to each other, as indicated in Fig. 1. 105

It is desirable that the electrodes should be arranged closely together and in staggered relation, as illustrated, in order that 110 as an article is passed between the electrodes upon the conveyer 20 or by any other means supported intermediate or moved between and past the electrodes, all parts thereof are subjected to the action of the 115 discharge; in other words, there should be no wide gaps in the line or curtain of discharge through which an article or portions of an article may be passed without being acted upon thereby.

120 As already indicated, the apparatus or machine illustrated herein produces low frequency electrical oscillations of commercial or slightly higher frequency. The said machine produces an alternating electric current but it will be understood by those skilled in the art relating to electrical machines that the current may be changed by 125

known means from an alternating to a unidirectional current.

In order to operate the apparatus illustrated, the switch 2 should be closed and the 5 variable or adjustable resistance 3 adjusted as desired. The capacity of the discharge spark may be controlled to some extent by adjusting the resistance 3 but it is principally dependent upon the transformers 5. 10 In order to secure the best results, the distance between the electrodes 6 and the surface of the top portion of the conveyer 20 or other supporting means should be only slightly greater than the height or thickness 15 of the objects or articles which are being treated in the apparatus. As the articles being treated are placed in position in the space between the electrodes they are acted upon by the electrical discharge which 20 takes place between the said electrodes, the passage of which through the objects effects or causes the destruction and killing of the insects, their eggs, larvæ or pupæ, which may be present. It is my understanding and 25 belief that the sparks are the portion of the discharge which is effective in destroying the insects, their eggs, larvæ or pupæ, and that the effluvæ does not destroy them.

In the treatment of tobacco in and by the 30 apparatus herein described, whether it be in the form of cigars or in bundles or bales prior to being converted into a manufactured product, the leaves thereof should be placed in the machine or apparatus for 35 treatment so that they extend substantially in parallel relation with the direction of the lines of discharge of the electric sparks between the opposing electrodes. If the tobacco is so placed that the lines of discharge 40 take place transversely of the leaves, the said discharges are apt to pass directly therethrough without spreading over their surfaces and in consequence are not likely to destroy all of the insects. It is also the case 45 that if the discharge takes place transversely of the leaves of the latter it is likely that the latter would be carbonized. The voltage should also be adjusted or varied so as to correspond with the capacity or conductivity 50 of the article being treated. For instance, the voltage necessary to treat successfully a column of tobacco of a certain definite size and height should be less than that employed in the treatment of a column of 55 the same size and height of some other substance of less conductivity, for instance, a cereal.

In the construction as illustrated, the electrodes are so arranged that the discharge 60 produced forms substantially a curtain so that if an article or object is passed between the electrodes, every part thereof is subjected to the action of the discharge and all of the insects, their eggs, larvæ or pupæ, are

destroyed. It is to be understood, however, 65 that my invention is not limited to the specific arrangement of electrodes illustrated. I have discovered that the said insects, etc., are killed immediately by the action of the said sparks, and I have discovered also 70 that the said sparks seek out the said insects, eggs, larvæ or pupæ, wherever they may be in the package and destroy them.

The broad subject matter of invention disclosed herein and not claimed is claimed in 75 my co-pending application filed January 7th, 1911, Serial No. 601,283.

The term "electrode" or "electrodes" employed herein is not one of limitation but of description and includes any terminal, as 80 for instance the ends of the secondary coil, from which electrical discharges take place.

Having thus described my invention, I claim:—

1. In an apparatus of the character described, the combination of a source of alternating electric current, transformers the primary coils of which are connected thereto, electrodes or terminals connected to the opposite ends of the secondary coils of said 90 transformers, the said electrodes or terminals being arranged in electrically independent pairs and in oppositely disposed groups and the electrodes or terminals in each group being situated in rows in staggered relation with respect to each other, and means consisting of non-conductive material for supporting articles or objects between the said electrodes or terminals whereby the electrical discharges between 95 the said electrodes may pass through said articles and objects and destroy any insects, their eggs, larvæ or pupæ which may be therein or thereon.

2. In apparatus of the character described, the combination of a source of electric current, a plurality of transformers of small capacity, a plurality of independent electrodes arranged in groups oppositely disposed with respect to each other and respectively having connection with said transformers, and means for supporting articles between said groups of electrodes.

3. In apparatus of the character described, the combination of a source of alternating electric current, a plurality of transformers of small capacity, a plurality of oppositely arranged electrodes connected to said transformers, the said electrodes being arranged in electrically independent pairs 120 and each pair having connection with a different transformer, and means for supporting articles between said electrodes.

4. In apparatus of the character described, the combination of a source of alternating electric current, a plurality of transformers of small capacity, a plurality of electrodes in oppositely arranged groups

having connection in electrically independent pairs with said transformers, the electrodes in each group being in staggered relation with respect to each other, and means
6 for supporting articles between said groups of electrodes.

In testimony that I claim the foregoing

as my invention, I have hereunto signed my name this 4th day of January, A. D. 1911.

FRANKLIN S. SMITH.
